CLAIM

We claim, the ornamental design for a compressor fan having a contoured fan blade, as shown and described.

DESCRIPTION

FIG. 1 is a perspective view of a compressor fan having a contoured fan blade, showing our new design;

FIG. 2 is a top view thereof;

FIG. 3 is a bottom view thereof;

FIG. 4 is a side view thereof;

FIG. 5 is a sectional view thereof, taken along line **5-5** shown in FIG. 2;

FIG. 7 is a detail view of the portion of the compressor fan having a contoured fan blade encircled in broken line in FIG. 2;

FIG. 8 is a sectional view thereof taken along line **8-8** shown in FIG. 2;

FIG. 9 is a sectional view thereof, taken along line **9-9** shown in FIG. 2;

FIG. 10 is a sectional view taken, along line **10-10** shown in FIG. 2;

FIG. 11 is a sectional view taken, along line **11-11** shown in FIG. 2; and,

FIG. 12 is a sectional view taken, along line **12-12** shown in FIG. 2.

The dash-dash broken lines in the drawings illustrate environmental subject matter only and form no part of the claimed design. The dash-dot-dash broken lines depict boundaries and form no part of the claimed design. The

(Continued)

dash-dot-dot-dash broken lines in FIG. 2 encircling a portion of the article reference a detail view and form no part of the claimed design.
